UNITED STATES PATENT OFFICE.

JOHN B. KRYSTEK, OF BOW ISLAND, ALBERTA, CANADA.

SAFETY-ENVELOP.

1,222,419.

Specification of Letters Patent. Patented Apr. 10, 1917.

Application filed August 24, 1916. Serial No. 116,756.

To all whom it may concern:

Be it known that I, JOHN B. KRYSTEK, a subject of the Czar of Russia, residing at Bow Island, in the Province of Alberta and 5 Dominion of Canada, have invented certain new and useful Improvements in Safety-Envelops, of which the following is a specification.

This invention relates to certain new and 10 useful improvements in safety envelopes.

The primary object of the invention is the provision of an envelop arranged with a plurality of adhesive surfaces and being of particular folded arrangement for utilizing 15 the same whereby the device is securely arranged when closed, preventing any removal of the missive without mutilating the device.

A further object is the provision of an 20 envelop adapted for folding and sealing at different opposite points after the missive has been positioned therein, providing an arrangement for preventing the unauthorized tampering with the contents thereof 25 without the same being readily detected by the appearance of the envelop.

In the drawings forming a part of this application and in which like designating characters refer to corresponding parts 30 throughout the several views:—

Figure 1 is a plan view of the envelop blank employed.

Fig. 2 is a rear elevational view of the envelop in its folded closed position.

Fig. 3 is a rear elevational view of the envelop when formed in its unfolded arrangement.

Fig. 4 is a front view thereof.

Fig. 5 is an elevational view of the same 40 when folded ready for sealing, showing the rear side thereof, and,

Fig. 6 is a perspective view of the same showing the front addressing side of the envelop.

45 The invention contemplates a blank 10 of the form shown in Fig. 1 formed of any desired flexible material of which the envelop is to be constructed. Said blank comprises a rectangular body 11 divided into 50 equal end portions 12 and 13 by means of a diagrammatically arranged fold line 14. Opposite end flaps 15 and 16 are provided upon the opposite ends of the body 11 foldable respectively upon lines 17 and 18 at the 55 opposite ends of the said body, both of the

said flaps being substantially triangular in form, the flap 16 having a squared or cut-off free end 19 while the flap 15 has a pointed free end 20.

The body 11 is further provided with oppositely arranged similar side flaps 21 foldable upon the lines 22 at the opposite longitudinal sides of the said body. The blank 10 is first arranged in envelop form as illustrated in Figs. 3 and 4 of the drawings by 60 folding the side flaps 21 inwardly upon the lines 22 and adhesively connecting the same by means of the flap 15 folded thereover upon the line 17, the flap 15 being secured in position by means of the adhesive edge 65 portions 23 of the flaps 21 which portions lie adjacent the flap 15 underlying the same when said flaps are folded in envelop arrangement.

By referring especially to Fig. 3, it will 75 be noted that the edge portions 13 of the flaps 21 are considerably removed inwardly of the marginal edges 24 of the flap 15 providing pockets for allowing the sealing insertion of the gummed side portions 25 of 80 the end flap 16 when the envelop is in its folded sealed arrangement hereinafter referred to, as best illustrated in Fig. 2.

With the envelop form as shown in Figs. 3 and 4, it will be evident that the missive 85 may be readily inserted therein adjacent the body-portion 13 and whereupon the envelop is then foldable upon the line 14 to the positions illustrated in Figs. 5 and 6 of the drawings. The edges 26 of the flaps 21 are 90 provided with adhesive portions 27 adapted to be adhesively secured to the adjacent face of the body-portion 12 while the flap 16 is foldable upon the line 18 for overlying the folded flap 15 and inserting the gummed 95 marginal portions 25 of the flap 16 beneath the edges 24 of the flap 15 by folding the edge portions of the flap 16 upon the lines 28.

The flap 16 is provided with an adhesive 100 upon its terminal edge 19 at one side of the flap for engaging the outer face of the flap 15 when the envelop is folded, an adhesive being provided upon both faces of the edge portions 25 thereof for securing 105 the flap 16 to both the flap 15 and the adjacent faces of the flaps 21.

With the envelop completely formed folded and sealed as illustrated in Fig. 2, the missive is securely inclosed therein, render- 110

ing it extremely difficult to gain access to the missive without destroying the material portions of the envelop.

What I claim as new is:—

- 5 A safety envelop comprising an oblong body centrally foldable upon itself, inwardly foldable side flaps and a pointed end flap adapted for overlying the said side flaps carried by the said body, the said end flap being adhesively secured to the said side flaps with normally free edges forming receiving pockets between the said end and side flaps, the said body and side flaps being
- 10

centrally folded with the said flaps positioned outermost when the envelop is in its 15 secured position, the marginal edge of the pointed flap being adhesively secured to the adjacent face of the body at the addressing side of the envelop, and a truncated sealing flap at the opposite end of the said 20 body having foldable marginal edges adhesively secured within the said pockets at the other side of the envelop.

In testimony whereof I affix my signature.

JOHN B. KRYSTEK.
